OPEN SHELF STORAGE UNIT

John W. Tapert, Detroit, Mich., assignor to Design Workshop, Inc., Detroit, Mich., a corporation of Michigan

Filed July 11, 1966, Ser. No. 3,022

Term of patent 14 years

(Cl. D33—3)

FIGURE 1 is a front perspective view of the open shelf storage unit showing my new design.

FIGURE 2 is a front elevational view of the open shelf storage unit shown in FIGURE 1, on a reduced scale.

FIGURE 3 is a rear elevational view thereof on a further reduced scale.

FIGURE 4 is a top plan view on the scale of FIG. 3.

FIGURE 5 is a side elevational view on the scale of FIGURE 3.

The appearance of the side of the open shelf storage unit not shown in FIGURE 5 is the same as that of the side shown.

I claim:

The ornamental design for an open shelf storage unit, substantially as shown and described.
